DESIGN FOR A SHAVING SOAP HOLDER

Oscar F. Grab, New York, N. Y.

Application May 7, 1943, Serial No. 110,148

Term of patent 14 years

To all whom it may concern:

Be it known that I, Oscar F. Grab, a citizen of the United States of America, residing at the Borough of Manhattan, in the city, county, and State of New York, have invented a new, original, and ornamental Design for a Shaving Soap Holder, of which the following is a specification, reference being had to the accompanying drawing, forming part thereof.

I claim:

The ornamental design for a shaving soap holder, as shown.

OSCAR F. GRAB.
